MICHAEL HARRY SCHUETZ, OF YANKTON, SOUTH DAKOTA, ASSIGNOR OF ONE-THIRD TO SAMUEL R. SCHUETZ AND ONE-THIRD TO JACOB C. SCHUETZ, BOTH OF YANKTON, SOUTH DAKOTA.

HOG-TROUGH.

1,185,440.

Specification of Letters Patent.

Patented May 30, 1916.

Application filed February 7, 1916. Serial No. 76,671.

To all whom it may concern:

Be it known that I, MICHAEL HARRY SCHUETZ, a citizen of the United States, and a resident of Yankton, in the county of 5 Yankton and State of South Dakota, have invented certain new and useful Improvements in Hog-Troughs, of which the following is a specification.

My invention is an improvement in hog 10 troughs, and the invention has for its object to provide a trough of the character specified, of one-piece construction, and a suitable support for the trough, that will prevent overturning, and wherein all danger of 15 damage to the trough from the forming of ice is eliminated, and wherein the expansion and contraction from temperature changes cannot injure the trough.

In the drawings: Figure 1 is a perspective view of the improved trough; Figs. 2 20 and 3 are sections on the lines 2—2 and 3—3, respectively, of Fig. 1, each looking in the direction of the arrows adjacent to the line; Fig. 4 is a top plan view of one end 25 with the hood or shield removed; Fig. 5 is a perspective view of a detail of the shield construction; Fig. 6 is a top plan view of a modified construction, and Fig. 7 is a section on the line 7—7 of Fig. 6.

30 In the present embodiment of the invention, the trough proper is formed from a single sheet of metal of suitable weight and character, the said sheet being bent to form a curved or arc-shaped body 1, having at 35 each side edge an outwardly extending flange 2. These flanges 2 are formed by folding the material of the sheet upon itself to provide a three-ply flange, as shown, and said flanges 2 are in the same plane.

40 The ends of the trough are formed by bending a portion of the sheet upward, as shown in Figs. 1 to 4, and the said ends 3 are corrugated as shown, that is, the material is bent in opposite direction to form on 45 each face a series of ribs alternating with a series of grooves.

The ends have their upper edges at approximately the same height as the flanges 2, and it will be noted from an inspection of 50 Figs. 4 and 5, that each of the ribs or flanges 2 is extended beyond the adjacent end, as indicated at 4, each of the said extensions 4 being approximately flush with the outermost portions of the corrugations at the 55 ends.

A hood or shield is arranged at each end of the trough for covering and concealing the upper edges of the ends, and for preventing displacement of the corrugations, and each of these hoods or shields is secured 60 to the extensions 4 of the ribs or flanges 2, and to the said ribs or flanges. Each of these hoods or shields is of channel material, comprising a body 5, and parallel side walls 6 and 7, respectively. The bodies 65 are of such width that when the shields are arranged as shown in Figs. 1 and 3, the side walls 6 and 7 of the shield will fit on opposite sides of the ends, engaging the corrugations, as clearly shown in Fig. 3.

70 Each hood or shield is provided at each end with a lateral extension 8, extending beyond the shield at the side 7, and each of the said extensions is channel-shaped, and is arranged with its channel inward. These 75 channel-shaped extensions are formed by bending a portion of the material inwardly approximately parallel with the plane of the shield, and the upper and lower portions of each section are spaced apart a sufficient distance to receive the adjacent extension 4 of the rib or flange 2.

The outermost side wall 6 of each shield is 80 of greater length than the innermost side wall 7, and each of the said side walls 6 extends from near the outer edge of one flange 2 to near the outer edge of the other flange. The extensions 4 and a portion of the flange 2 is received between the upper and lower walls of each extension 8, and it will be 85 noted that the extensions 8 have openings 9 for receiving rivets 10 which are passed through the walls of the extensions and through the flanges or ribs 2, to rigidly connect the hoods or shields with the flanges 2.

90 Supporting legs are arranged at the ends of the trough, each of the legs comprising a body portion 11 of arc shape, and arms 12 extending upwardly and inwardly from the body. Each of the body portions 11 is arranged with its convex face upward, and the convexity of each body is such that when the legs are connected to the trough in a manner to be presently described, the center 95 of each body 11 will engage the center of the body 1 of the trough, as shown in Figs. 2 and 3. The arms 12 extend upwardly and inwardly, and at its upper end each arm is provided with a lateral outwardly extending lug 13 which abuts the under face of the 100 105 110

adjacent extension 8, and one of the rivets 10 at each corner of the trough is passed through the adjacent lug 13 of the adjacent leg. Thus the rivets 10 not only connect 5 the extensions 8, and as a consequence the hoods to the flanges or ribs 2, but they also connect the legs 11—12—13 to the trough.

In the embodiment shown in Figs. 6 and 7, the trough comprises a body 14, and flanges 10 15 constructed in the same manner as the flanges 2 of Figs. 1 to 5, and the ends 16 of the trough are corrugated in the same manner as the ends 3 of the trough 1.

The trough is also provided with the 15 hoods or shields 17 at its ends, and the legs 18 are connected to the trough in the same manner as the legs 11—12—13 of Figs. 1 to 5. The trough, however, is provided with a vertical partition 19, extending the full length 20 thereof, from one end to the other, and from the top to the bottom. This partition is held in place by transverse straps or bars 20, the said straps or bars being secured to the flanges 15 at their ends, by means of rivets 25 21 or the like. The trough is thus divided into compartments, and the straps or bars 20 further sub-divide these compartments, so that the hogs in feeding are separated from each other.

30 The cross section of the trough body is a semicircle or less, and should the contents of the trough freeze solid, the trough will not be broken, since there is nothing to prevent the ice from bulging upward to relieve 35 the pressure. Since there is no solder used in the construction, overheating does not injure the trough.

The particular arrangement of the legs makes overturning of the trough difficult, for 40 the supporting base of the trough is of larger area than the trough itself. The improved trough may be overturned, however, and trampled upon without any danger of damage to the same.

45 It will be understood that the troughs may be made of any size desired, and of any suitable material. It will also be understood that drain openings may be provided in the trough if found advisable.

50 I claim:

1. A hog trough composed of a sheet of metal bent to form a concave arc-shaped body having at each side edge an outwardly extending reinforced flange or rib formed by

folding the material upon itself, and having 55 integral ends bent in opposite directions to form a series of corrugations, a hood or shield at each end of the trough and of channel shape, and comprising a body resting on the upper edge of the end, and side 60 walls at opposite sides of the corrugations, each hood or shield having a channel-shaped extension at each end for engaging over the adjacent rib or flange of the body, a leg at each end of the trough, each leg comprising 65 a convex body engaging the body of the trough at its center, and arms extending upwardly and inwardly from the ends of the body, each arm having an outwardly extending lug abutting the under face of the adjacent 70 extension of the adjacent hood or shield, and rivets connecting the extensions and the ribs or flanges.

2. A hog trough formed of a sheet of metal bent to form an arc-shaped body having 75 at each side edge an outwardly extending rib, or flange, and having integral ends bent in opposite directions to form a series of corrugations, a hood or shield at each end of the trough and of channel shape, and comprising a body resting on the upper edge of the end and side walls at opposite sides of the corrugations, each hood or shield being 80 rigidly connected with the ribs of the body, and a leg at each end of the trough, each leg comprising a convex body engaging the body of the trough at its center, and the supporting surface for the trough at its ends, and arms extending upwardly and inwardly from the ends of the body secured to 85 the flanges or ribs of the body.

3. A hog trough composed of a sheet of metal bent to form a trough-shaped body having at each side edge an outwardly extending rib or flange and having integral 95 ends bent in opposite directions to form a series of corrugations, a hood or shield at each end of the trough and of channel shape, and comprising a body resting on the upper edge of the end and side walls at opposite 100 sides of the corrugations, each hood or shield being rigidly connected with the ribs of the body, and a leg at each end of the trough.
